UNITED STATES PATENT OFFICE.

ALEXANDER L. FAUST, OF CINCINNATI, OHIO, ASSIGNOR TO NATIONAL MARKING MACHINE COMPANY, OF CINCINNATI, OHIO, A CORPORATION.

LAUNDRY MARKING-TAG-ATTACHING MACHINE.

Application filed August 23, 1921. Serial No. 494,682.

At the present time laundry articles are marked for identification in several ways, for instance by printing machines in which the owner's name or mark is printed direct 5 on the laundry articles with indelible ink. These printing machines, however, cannot be used on dark colored laundry articles, such, for instance, as black stockings, and furthermore the mark itself on certain articles is very objectionable on account of its 10 appearance, as, for instance, on ladies' handkerchiefs.

For use in marking articles such as black stockings, white cloth tags are sometimes 15 permanently sewed to the article, and then the identification mark is made with a printing machine on these white tags. This procedure is objectionable because it is too expensive, the labels permanently fixed to the 20 laundry articles are objectionable to many people, and the use of this plan is applicable only to articles such, for instance, as stockings.

Metal tags bearing suitable identification 25 marks are also provided, and are attached to the laundry articles by some sort of pin or clamp device. These, however, are objectionable because when delicate handkerchiefs are thus identified and passed through 30 the washing and ironing process, the metal tags frequently tear the delicate fabrics, and they also occasionally become detached and laundry articles are thereby lost.

My object is to provide a machine of 35 simple, durable and inexpensive construction, in the nature of an attachment to a sewing machine, for the purpose of identifying laundry articles and avoiding all of the objections heretofore noted in connection 40 with other methods of marking.

More specifically it is my object to provide laundry marking tags formed of flat pieces of woven fabric or tape, and upon which the laundry identification mark is 45 printed, and to provide these fabric tags in large numbers all bearing the same identification mark, so that they may be produced very cheap.

A further object is to provide simple and 50 inexpensive containers for the previously printed cloth tags, which containers may be readily, quickly and easily selected from a

rack containing a large number of the containers, and set into the label attaching machine for use.

A further object is to provide a device of simple, durable and inexpensive construction, designed to be readily and quickly applied to a sewing machine, and which device is designed to receive a container having 55 said fabric tags therein, said attachment being so arranged that a laundry article may be placed on the sewing machine and when the operator touches a lever one of the tags will be removed from the container and 60 placed in position on the laundry article to be marked, and then the sewing machine will be automatically actuated to sew the tag to the fabric, and as soon as this is accomplished the sewing machine will be automatically stopped, whereby the operator may quickly, conveniently and easily attach the tags to the laundry articles without any attention to the machine other than the placing of the laundry article in position 65 and the touching of a lever.

A further object is to provide a tag of this kind which may be attached to the laundry article in the manner described, for identification purposes, which tag will not 70 in any way injure the article, as is sometimes done with metal tags, and no permanent mark of any kind will be made on the article, and the article may be thoroughly washed under the tag, which is sometimes 75 impossible with metal tags, and when the washing, ironing and assorting have been completed all the tags may be readily and quickly removed and thrown away, thereby avoiding the objections incident to the use 80 of permanently applied tags, or identification marks printed on the laundry articles.

My invention consists in the construction, arrangement and combination of the various parts of the device, whereby the objects contemplated are attained, as hereinafter more fully set forth, pointed out in my claims, and illustrated in the accompanying drawings, in which:

Figure 1 shows a side elevation of a part 100 of a sewing machine having my tag applying attachment applied thereto.

Figure 2 shows a rear elevation of same.

Figure 3 shows an enlarged, detail, sec-

tional view, illustrating the main shaft of the tag applying attachment and the parts mounted thereon.

Figure 4 shows an enlarged detail view illustrating the cam device for operating the sewing machine controlling switch.

Figure 5 shows an enlarged, detail, sectional view through the sewing machine presser foot, and illustrating the part of the device for removing the tags from the container and delivering them to position on the laundry article and beneath the presser foot.

Figure 6 shows an enlarged, detail, sectional view, on the line 6—6 of Figure 7.

Figure 7 shows a vertical, central, sectional view through the lower end of one of the tag containers and the supporting socket in which it is placed in the tag attaching machine. The dotted lines in this figure indicate the position of the tag removing device and a tag after it has been removed from the container.

Figure 8 shows a side elevation of a part of a sewing machine with my device attached thereto, illustrating the motor for operating the sewing machine controlled by the tag attaching device.

Figure 9 shows an enlarged, detail, sectional view of a part of a laundry article having one of my improved tags sewed thereto in the manner in which the sewing is done with my improved machine.

Figure 10 is a top or plan view of same. Figure 11 shows a view similar to Figure 1, but taken from the opposite side.

Figure 12 shows a view similar to Figure 1 and illustrating a modification, with the tag carrying device in position for forcing a tag under the presser foot, and with the automatic starting and stopping device in the position it assumes when the label carrying device is at the lower limit of its movement.

Figure 13 shows an enlarged detail view illustrating the ratchet device for stopping and starting the tag conveying device; and

Figure 14 shows a perspective view illustrating one of the tag containers mounted in the supporting socket.

Referring to the accompanying drawings, I have used the reference numeral 10 to indicate that portion of a sewing machine therein illustrated. It is provided with an electric motor 11, by which it is operated. This sewing machine is provided with a vertically movable presser foot 12, mounted on a presser bar 13 which is normally held downwardly by the spring 14. 15 indicates the sewing machine needle, and 16 the base plate on which the work is supported during the sewing operation.

The sewing machine proper forms no part of my present invention, and hence is not herein specifically illustrated or described.

I prefer, however, to use a sewing machine

of the type commonly known as a barring machine, and which will make stitches that will not readily unravel, so that a tag may be sewed to a laundry article and the tag held firmly enough so that it will not be displaced during the washing or assorting process, and then the stitches may be readily and easily cut with a pair of scissors to remove the tag.

My improved attachment comprises a main supporting plate 17, which is fixedly secured to a part of the sewing machine adjacent to the presser foot. This plate 17 supports a small electric motor 18, with its shaft 19 extended downwardly. On the lower end of the shaft 19 is a small worm gear 20. Extended transversely of the shaft 19 is the main driving shaft 21 of my improved attachment. On this driving shaft 21 is a worm gear 22, loosely mounted, and it is in mesh with the worm gear 20 by which it is driven. On the interior of the worm gear 22 is a ratchet toothed rim 23, shown in Figure 13, for purposes hereinafter made clear. The worm gear 22 is constantly driven by its motor 18, and when it is desired to have the tag attaching device operate, the shaft 21 is operatively connected with the worm gear 22 as follows:

24 indicates a treadle pivoted to a suitable support and connected by a rod 25 with a lever 26, which lever has a shoulder 27 at its outer end. The lever is fulcrumed to a suitable support 28 on the plate 17, and said lever is also provided with an upwardly extending arm 29 to which a spring 30 is applied to yieldingly hold the end of the lever on which the shoulder 27 is formed, downwardly. Pivottally mounted on the same support 28 is an arm 31, the downward movement of which is limited by a stop device 32. Fixed to the shaft 21 is an upwardly extending arm 33, its upper end being designed to engage the arm 31, as shown in Figure 1. This arm 33 has on its lower end, as clearly shown in Figure 13, a laterally extending lug 34 with an extensible coil spring 35 mounted thereon and extending upwardly. Fulcrumed to the arm 33 is a lever 36, extended upwardly and designed to coact with the shoulder 27 of the lever 26, as will hereinafter appear. On the lower end of the lever 36 is fixed a pawl 37, its under surface being engaged by the spring 35, which tends to hold it outwardly into engagement with the ratchet teeth 23.

When these parts are all at rest, as shown in Figure 1, the worm gear 22 is turning loosely on the shaft 21. When, however, the treadle 24 is depressed, the shoulder 27 is elevated above the lever 36 so that the upper end of this lever may be moved by the spring 35 in such direction that the pawl 37 may engage the ratchet teeth 23. During this operation the arm 31 prevents the lever 33 from moving in one direction, so that

it forms a solid support for the spring 35 to work against in pushing the pawl 37 into engagement with the ratchet teeth 23. As soon, however, as said pawl has been brought 5 into engagement with the ratchet teeth 23, then the shaft 21 on which the arm 33 is fixed begins to rotate in unison with the worm gear 22, and this rotation continues for one complete revolution or until the lever 10 36 is brought into engagement with the shoulder 27, when it is again stopped and the pawl 37 thereby released from engagement with the ratchet teeth 23, as shown in Figure 13. At the same time the arm 33 15 elevates the lever 31 and moves it to the position shown in Figure 1, where it will again serve to hold the arm 33 rigidly in position against movement in one direction.

From the description of the foregoing 20 mechanism, it is obvious that when the treadle has been depressed, the shaft 21 will make one complete revolution and then stop.

During the revolution of the shaft 21 it is desirable that during the first part of the 25 revolution the tag affixing mechanism be operated to place a tag in position, and then immediately thereafter, or during the latter part of the revolution of the shaft 21, the sewing machine be operated to sew the 30 tag to the article to be identified. I have provided for these operations as follows:

Fixed to the shaft 21 is a crank wheel 38, having a crank pin 39 thereon, to which is pivoted a rack bar 40. This rack bar is 35 mounted in a suitable guide 41, and is in mesh with a pinion 42. A rotation of this pinion 42 will operate the tag affixing device, as will hereinafter be made clear. The arrangement of these parts is such that during 40 the first part of the revolution of the shaft 21, the tag will be brought to the position for sewing, and then during the last part of the revolution the tag carrying mechanism 45 will be returned to normal position, as shown in Figure 1.

In order to automatically operate the sewing machine at the instant when the tag has been brought to position for sewing, I have provided the following mechanism:

Fulcrumed to the plate 17 is a bell crank 50 lever 43, having a slotted arm 44 designed to receive a pin 45 on the sewing machine shaft 13. On the downwardly extending part of the lever 44 is a roller 46, and adjacent to this roller is a cam 47 fixed to the shaft 21. The shape of this cam is such that during the first portion of the movement of the shaft 21 the roller 46 is not moved, and during the last part of the rotation of the 55 shaft 21 the roller is permitted to move toward the shaft 21, which movement causes the spring 14 to move the presser foot downwardly and at the same time brings the electric contact point plate 48 into engagement 60 with the mating contact point 49, which

closes a circuit through the conductor wires 50 leading to the motor 11, which operates the sewing machine. Hence the sewing machine is operated during the latter part of the rotation of the shaft 21, and is automatically stopped at about the completion 70 of a rotation of the shaft 21.

I shall next describe the means for supporting the tags and for moving them one by one to sewing position.

The tags proper are indicated in Figure 10 by the numeral 51. As herein illustrated, the tags are preferably rectangular in shape, and may be made of tape having two selvage edges. The shape of the tag, however, is not important, and may be varied as may be desired, and it is not of any particular importance that the edges be selvaged. Each tag has printed upon it a laundry identification mark of the kind in ordinary use. All 85 of the tags bearing a certain particular mark are placed into a container 52. I preferably have this container made of paper or fiber, and it is to be understood that there is to be a separate container for each set of 90 tags bearing a different identification mark. For instance, assuming that in a certain laundry it is desired to use two hundred different identification marks, then there will be two hundred of said paper containers, each filled with tags bearing the same identification mark, but the tags in one container will have a different identification 95 mark from the tags in each of the other containers.

In this connection, it is obvious that these tags bearing identification marks may be supplied to laundries very cheaply, because the identification marks may be printed thereon before they are supplied to a laundry, and the printing may be done on an ordinary printing machine and in large quantities.

These containers 52 are preferably open at both ends, and are uniform throughout 110 their length, and I also preferably provide a weight 53 to rest upon the top of the tags in the container to normally force them downwardly toward the bottom.

Mounted upon the side of the sewing machine, adjacent to but above the presser foot, is a socket 54, to slidably receive and support the lower end of the container 52, as shown in Figure 7. This socket is supported in a suitable bracket 55. The bottom 56 of the socket, as shown in Figure 6, is provided with two slots 57, spaced apart. The weight 53 forces the tags 51 downwardly until they rest upon the bottom 56, and the front of the socket 54 adjacent to the bottom is cut away 120 so that the lowermost tag may be engaged and drawn forwardly from the socket.

In this connection it is desirable that only one tag at a time be thus drawn out, and it sometimes happens that these tags vary in 130

thickness. For this reason I have provided a gauge device 58, vertically adjustable within the socket at the open front thereof near the bottom. This gauge device is made 5 vertically adjustable by the set screw 59 in the lug 60 entering a screw-threaded opening in the lug 61 of the gauge device, as clearly shown in Figures 6 and 7. By this means the gauge device may be so set that only one 10 tag at a time may be drawn out from the under portion of the socket.

In order to provide for moving the tags from the socket to sewing position, I have provided the curved, yielding guide plate 15 62, with its upper end arranged just in front of the gauge device 58 and its body portion curved outwardly, downwardly and then inwardly to a position slightly above the base 16 and adjacent to the presser foot. The 20 yielding feature of the guide plate permits it to adjust itself to different thicknesses of the cloth.

The device for engaging the tags and moving them to sewing position comprises a 25 shaft 63, loosely mounted in a support 64 on the frame plate 17, which shaft has the pinion 42 fixed thereon and in mesh with the rack bar 40. Fixed to the shaft 63 are two upwardly extending arms 65, and each arm 30 has at its upper end a spring wire hook 66, and this hook is yieldingly held upwardly and in a direction toward the guide plate 62.

In use with this portion of the device, and assuming that the rack bar 40 is moved, then 35 the spring wire hook 66 will engage the lower tag, as shown in Figure 7, and a continued movement thereof will convey the lower tag forwardly from the container to the under or inner surface of the guide 62, 40 and the said tag will be moved on said guide downwardly until the tag is projected under the presser foot and on top of the laundry article 67 which is resting upon the base 16, and it will be held by said hooks in this 45 position until the presser foot is lowered and the rack bar moved in an opposite direction to again elevate the arms 65, the hooks being so shaped that during this elevating movement they will withdraw from the tag.

50 In practical operation in a laundry, the operator takes a bundle of laundry articles and then selects one of the tag containers from the case or rack in which they are placed, and places this container with its 55 tags in the socket in front of the sewing machine, it being understood that the tags in this container have all been previously provided with the same identification mark. Then the operator places the laundry articles, one at a time, on the sewing machine base beneath the presser foot, and then 60 touches the treadle 24, with the result that the hooks 66 will be moved forwardly, with the lowermost tag engaged by them, and the 65 tag will then be held by the hooks against

the guide 62 until the hooks reach the lower limit of their movement, in which position the tag is held under the presser foot and on top of the article to be marked. Then the sewing machine is automatically operated, 70 and the tag sewed to, the article to be marked, while the arms bearing the hooks 66 will return to position in engagement with the next tag in the bottom of the container.

All of the articles in the particular bundle are supplied with tags from the same container. Then they may be put through the ordinary laundry processes of washing, ironing, assorting, etc., and during these processes it is obvious that the flexible fabric tag will not in any way interfere with the thorough washing of the laundry article beneath the tag. Furthermore, the tag does not in any way interfere with the process of ironing, and there is no danger of having delicate fabrics torn on account of the fabric tags.

80 After the laundry articles have all been assorted, then the operator removes all of the tags by cutting the stitches that connect them to the laundry articles, and the tags are thrown away, and the laundry articles are returned without any identification mark on them to disfigure them.

Obviously the danger of loss of an article 85 in the laundry processes is, by my improved tag, reduced to a minimum, because a tag is firmly sewed to each article so that it cannot become accidentally removed in the laundry processes, and furthermore there is no danger of the tag becoming caught or entangled with other garments, or with a washing or ironing machine, so that there is practically no danger of the tag becoming torn loose from the garment to which it is attached. 90 Hence loss to the laundry by reason of lost or torn laundry articles is reduced to a minimum.

95 The average bundle of laundry articles contains perhaps thirty pieces, and one of my cartons full of tags contains approximately a thousand tags. It is to be understood in this connection, that it is only necessary to supply enough of the containers, each bearing tags having different identification 100 marks, for use in the laundry during a certain period of time, say, for instance, one day. At the end of the day all of the articles that were marked during the day's work have been assorted and distributed, so 105 that on the next day, or the next period of time for the laundry operation, the same containers of tags may be used over again, so that it is not necessary to refill the containers after a single bundle of laundry articles has been marked.

110 I claim as my invention:

115 1. In a device of the class described, the combination of a container designed to hold a series of disconnected independent tags 120

- arranged one above the other, a device for withdrawing the tags one at a time from the container and for moving them to position resting upon a garment to be marked, 5 said device including a pointed finger to engage and penetrate the under surface of the tag, and means automatically actuated upon a movement of said tag withdrawing device for securing the tag to a garment.
- 10 2. The combination with a sewing machine having a presser foot, of a container designed to receive a series of independent disconnected tags arranged one above the other, means for supporting the container adjacent 15 to the sewing machine, means for withdrawing the tags one at a time from the container and for moving them to position under the presser foot of the sewing machine, said means including a pointed finger to engage 20 and penetrate the under surface of the tag, and means for automatically actuating the sewing machine upon the completion of the movement which brings the tag to position under the presser foot.
- 25 3. The combination with a sewing machine having a presser foot, of a container designed to receive a series of independent disconnected tags arranged one above the other, means for supporting the container 30 adjacent to the sewing machine, means for withdrawing the tags one at a time from the container and for moving them to position under the presser foot of the sewing machine, said means including a pointed finger 35 to engage and penetrate the under surface of the tag, means for automatically actuating the sewing machine upon the completion of the movement which brings the tag to position under the presser foot, and 40 means for automatically lowering the presser foot to position for holding the tag in position for sewing to a garment.
4. The combination with a sewing machine having a presser foot, of a container designed to receive a series of independent disconnected tags arranged one above the other, means for supporting the container adjacent 45 to the sewing machine, means for withdrawing the tags one at a time from the container and for moving them to position under the presser foot of the sewing machine, said means including a pointed finger 50 to engage and penetrate the under surface of the tag, means for automatically actuating the sewing machine upon the completion of the movement which brings the tag to position under the presser foot, and 55 means for automatically lowering the presser foot to position for holding the tag in position for sewing to a garment.
- 60 5. The combination with a sewing machine having a presser foot, of a container designed to receive a series of independent disconnected tags arranged one above the other, means for supporting the container adjacent to the sewing machine, means for withdrawing the tags one at a time from the container and for moving them to position under the presser foot of the sewing machine, said means including a pointed finger to engage and penetrate the under surface of the tag, means for automatically actuating the sewing machine upon the completion of the movement which brings the tag to position under the presser foot, and means for automatically lowering the presser foot to position for holding the tag in position for sewing to a garment.
- 65 6. The combination with a sewing machine having a presser foot, of a container designed to contain a series of independent disconnected tags arranged one above the other, there being an opening in the bottom portion of the container through which the tags may be removed, an arcuate guide adjacent to said opening extending from the opening to a point adjacent to the presser foot of the sewing machine, and means for engaging the undermost tag in the container and moving it out through the opening in the container and downwardly against said arcuate guide to a reversed position under the presser foot without disturbing or moving the other tags within the container, said guide having a yielding lower end whereby it may adjust itself to garments of different thicknesses on the sewing machine.
7. In a device of the class described, the combination with a sewing machine having a presser foot, of a container designed to contain a series of independent disconnected tags, said container having an opening at its bottom through which the lowermost tag may be removed, two arms spaced apart from each other and capable of arcuate movement, and spring actuated hooks carried by said arms and designed when in one position to engage the lowermost tag, and when operated to carry said tag outwardly from the container and through an arc to an inverted position under the presser foot of the sewing machine.
8. In a device of the class described, the combination with a sewing machine having a presser foot, of a container designed to contain a series of independent disconnected tags, said container having an opening at its bottom through which the lowermost

tag may be removed, two arms spaced apart from each other and capable of arcuate movement, spring actuated hooks carried by said arms and designed when in one position to engage the lowermost tag, and when operated to carry said tag outwardly from the container and through an arc to an inverted position under the presser foot of the sewing machine, and an arcuate guide to co-
10 act with said spring hooks.

9. In a device of the class described, the combination with a sewing machine, of a container designed to contain a series of independent disconnected tags, means for with-
15 drawing the tags one at a time from the container and placing them in position for sewing, a shaft, means operated by said shaft for actuating the said tag withdrawing mechanism, a constantly rotating member
20 associated with the shaft, manually operat-
ed means for connecting the constantly rotat-
ing member with the shaft, so that the shaft may be driven a complete revolution, said means for connecting the constantly
25 rotating member with the shaft being also designed to stop the shaft at the end of a complete revolution, and means operated by said shaft for automatically operating the sewing machine after the shaft has moved
30 through the initial part of its revolution, said means being automatically moved to in-

operative position upon the completion of the rotation of the shaft.

10. The combination with a sewing ma-
chine having a presser foot, of an electric 35
motor for operating the sewing machine, a
container designed to contain a series of in-
dependent disconnected tags, means for re-
moving the tags from the container and
placing them in position under the presser 40
foot of the sewing machine, a shaft, a con-
stantly driven rotatable member loosely
mounted on said shaft, a crank wheel fixed
to said shaft, a rack bar connected to said
crank wheel for operating the said tag re- 45
moving device, a cam fixed to said shaft, a
lever arranged to be operated by said cam,
said lever being connected to the presser
foot of the sewing machine and being so ar-
ranged that when the said rack bar has 50
moved past the initial stage of its movement
the said lever will be actuated and the presser
foot moved downwardly, and an electric
switch device in the circuit of the sewing
machine motor, associated with said lever 55
and arranged to close the circuit when the
presser foot has been moved downwardly,
said cam being also so arranged as to re-
turn the lever to position for elevating the
presser foot at the completion of a single 60
revolution of said shaft.

ALEXANDER L. FAUST.
